UNITED STATES PATENT OFFICE

144,281

DESIGN FOR A GAME BOARD

Edward J. Anselman, Chicago, Ill., assignor to Setney Products Company, Chicago, Ill.

Application August 3, 1945, Serial No. 121,189

Term of patent 7 years

(Cl. D34—5)

To all whom it may concern:

Be it known that I, Edward J. Anselman, a citizen of the United States, residing at Chicago, in the county of Cook and State of Illinois, have invented a new, original, and ornamental Design for Game Boards, of which the following is a specification, reference being had to the accompanying drawing, forming part thereof.

Fig. 1 is a plan view of the game board, showing my new design; and

Fig. 2 is a longitudinal section of one of the halves of the game board, on an enlarged scale.

I claim:

The ornamental design for a game board, as shown.

EDWARD J. ANSELMAN.
